(57) **CLAIM**

I claim the ornamental design for the refillable napkin dispenser, as shown and described.

DESCRIPTION

FIG. 1 is an oblique elevational view as seen from the left front edge of a refillable napkin dispenser showing my new design;

FIG. 2 is a front elevational view thereof;

FIG. 3 is a left side elevational view thereof, the right side being a mirror image;

FIG. 4 is a rear elevational view thereof;

FIG. 5 is a top plan view thereof; and,

FIG. 6 is a bottom plan view thereof.
